UNITED STATES PATENT OFFICE.

JAMES BLAIR GIBBS, OF MEXICO, AND HENRY BOOZER, OF MANSFIELD, OHIO.

CORN-HARVESTER.

SPECIFICATION forming part of Letters Patent No. 431,576, dated July 8, 1890.

Application filed November 25, 1889. Serial No. 331,412. (No model.)

To all whom it may concern:

Be it known that we, JAMES BLAIR GIBBS and HENRY BOOZER, citizens of the United States, residing, respectively, at Mexico, county of Wyandotte, State of Ohio, and at Mansfield, in the county of Richland and State of Ohio, have invented certain new and useful Improvements in Corn-Harvesters; and we do hereby declare that the following is a full, clear, and exact description of the invention, which will enable others skilled in the art to which it appertains to make and use the same, reference being had to the accompanying drawings, and to the letters of reference marked thereon, which form part of this specification.

Our invention relates to corn-harvesters, and has for its object to construct a harvester that shall be portable, light, and convenient of management, with the requisite strength to perform the work of cutting and gathering the corn into bundles ready to be tied, and then delivering the same from the table to the ground.

A further object is to provide for adjustability of the parts to conform to different heights of corn.

A further object is to provide means for delivering the cornstalks vertically upon the table and straightening the same to form a compact bundle.

A further object is to provide compressing-arms for closely compacting the stalks into a bundle while upon the table, and after being bound to set the bundle in an upright position upon the ground.

The invention consists in the parts and combination of parts hereinafter described, and pointed out in the claims.

In the drawings, Figure 1 is a perspective view of a harvester constructed in accordance with our invention. Fig. 2 is a plan view of the same, the upper guides and their supporting-arms being omitted. Fig. 3 is a detail view of the driving mechanism. Fig. 4 is a view showing the miter-gear and axis in full lines and the revolute knife and bearing in section to illustrate the adjustability of the axis from a vertical to an inclined position to incline the knife to cause the same to cut upon a slant. Fig. 4^a is a de-

tail edge view of the metal bar for securing adjustment to the rotary knife. Fig. 5 is a front elevation of the adjusting mechanism. Fig. 6 is an elevation of a section of the shaft carrying the sweep-arms and the means employed to cause the same to have an intermittent rotary movement. Fig. 7 is an elevation of a section of the table, showing the means employed for raising and lowering the same. Fig. 8 is a plan view of the compressing-arms and the lever by which to raise the same to lift the bundle of stalks from the table. Fig. 9 is a view of the shaft upon which the compression-arms are mounted, showing the movable wedge for closing the arms and the shoulders for abutting against the under side of the arms to raise the same when embracing the bundle. Fig. 10 is a detail view showing one of the telescoping standards and the arm yieldingly and pivotally secured thereto for supporting one of the guides for the cut stalks. Fig. 11 is a detached view of a portion of the frame-work, showing the caster-wheel frame and the journal for the shaft upon which the compression-arms are secured, and also an automatically-locking support for the framework when delivering a bundle of stalks to the ground. Fig. 12 is a detail view of one of the series of arms employed in moving the corn to the knives and the cut corn upon the lower table.

A designates the main axle, upon which are keyed wheels A', by which to render the harvester portable.

B designates a base-frame mounted upon axle A, said frame consisting of a platform supported by longitudinal sills B' and transverse sills B'', there being a platform B''', supported therefrom by means of cross-timbers B''', (shown in dotted lines in Fig. 1,) and which are secured centrally to a section C of a post C', the upper section C being arranged to slide telescopically upon the lower section when actuated by a lever C'', fulcrumed upon a standard C''' and provided with a spring-dog C''', adapted to engage into recesses in the sections C and C' to hold the platform to any desired adjustment as to height, the corners of the table being held in place by means of telescopic posts D, one section of which is secured to the sills, the

opposite section being secured to the platform.

D' designates inclined posts secured to the longitudinal sills, and to which are secured 5 braces D'' by means of bolts D''', passed through longitudinal slots D'''' in the braces, the elongation of the slots being sufficient to allow the braces to rise in unison with the platform when being elevated, and the braces 10 being secured by means of nuts upon the bolts D''', the upper ends of the braces being pivotally secured to the platform.

E designates sills supplemental to sills B' and inclined outwardly therefrom at the forward end of the harvester, thereby forming 15 a V-shaped recess between the sills, into which the uncut corn is caused to enter to be cut, as will be more fully explained. Sills E are secured to sills B' at their rear ends, and are 20 provided with an inclined fender or guard E'' for the wheels, from which extends a brace E''', which is secured to vertical standards E'''', extending from the sill in parallel relation with post C'. The rear edge of the 25 platform B'' is rounded at each corner and cut away at the center to form a convenient space in which to assemble a stool or bundle of cornstalks prior to being bound.

F designates a curved frame-work extending from the side of the platform B''' to the point in rear thereof at which the cut-away portion commences, the frame-work being supported by means of tubular sections F', secured thereto, which telescope with the 35 standards E'''' when raised or lowered by means of levers G, fulcrumed upon standards G', framed into the sills E, and may be held to any desired adjustment by means of a spring-catch, such as described with relation to sections C and C' of the central post, or in any preferred manner. Frame-work F is further stayed by means of an inclined brace F'', flexibly secured thereto and to standards F''', corresponding to standards D' 40 of sill B', and being secured to standards F'''' by means of bolts F''''', passed through longitudinal slots F''''' of a length to allow the frame-work to be raised the desired distance.

H designates a guide having an inner contour corresponding to the outer edge of the rear side and the rounded corner of the platform B''', said guide being secured to the frame-work F by means of springs H', (shown in dotted lines, Fig. 2,) which allow the guides 55 to have a yielding pressure against the stalks as they are passed against the same.

I designates a guide of like contour to that of guide H and arranged above the same, being held in place by means of arms J, pivotally secured upon tubular sections F' and urged 60 toward the platform B''' by means of a coiled spring J', bearing against a stud J'' upon section F' and the arm.

K designates a guide-rail secured upon the 65 platform and having a like contour to that of the edge of the platform, which rail, in connection with rails H and I, serves to support

the upper portion of the stalks in the passage of the stalks to the rear of the machine, their lower ends being guided by fenders K' and 70 K'', secured to the lower portion of the frame of the machine.

L designates a bifurcated frame journaled upon the axle A, the outer end having a platform L' secured thereon, upon which the operator may stand, and there being a center-wheel M, journaled in a standard M', pivotally secured to the frame L to sustain the weight of the operator thereon.

N designates a step secured to the lower frame-work, and into which is journaled a standard N', provided with a fixed curved guide N'' a short distance above the frame-work and a pair of gripping-jaws O at some distance above the guide N''. Jaws O are 85 pivotally mounted upon standard N', and are adapted to be closed by means of a wedge O', movable upon the standard, the pointed end of the wedge being caused to enter a slot O'' in a web O''' upon the rear side of the arm 90 and bear against the web of the opposite arm as the wedge is urged within the slot to cause the arms to close, when upon urging the wedge within the slot to its full extent shoulders P are caused to contact with the arms and raise 95 the same vertically upon the standard N' to raise the stool or bundle of corn grasped by the arms, as will more fully appear.

P' designates a gear keyed upon axle A and meshing with a pinion P'' upon a counter-shaft P''', journaled in the framing, the counter-shaft being in parallel relation with the axle and having keyed thereon a bevel-gear Q, which intermeshes with a like gear Q' upon a vertical shaft R, having a squared end to enter a squared socket R' telescopically, into which is secured the lower end of a shaft Q'', which passes through the platform B'' and has a sleeve Q''' secured thereon, formed with a ratchet-face Q'''' upon the upper end, 110 into which engages the ratchet-face of the lower end of a sleeve S, upon which is secured an arm S', having extensions in opposite directions from the shaft, as shown in Figs. 1, 2, and 7, sleeve Q''' being normally held in 115 engagement with sleeve S by means of a spiral spring S''''.

To the outer ends of arms S' are secured upper and lower sweeps T and T', respectively, the upper sweep T being keyed to a shaft T'', which passes through the arm S' and is attached to the lower sweep T' below the same, there being a coiled spring T''' secured to the arm and sweep T', whereby the sweep may move in radial line with the arm until meeting an obstruction sufficient to overcome the tension of the spring, when the sweep may swing back and pass the obstruction and resume its radial parallelism with the arm, the springs in their normal position 120 serving also as a stop to prevent the arms swinging back too far.

Upon the outer end of shaft P''' is keyed a bevel-gear U, which intermeshes with a

bevel-gear U', secured upon a rotary knife U'', whereby the knife is given a rotary motion when the wheels A' and axle A are revolved.

5 V designates a knife secured upon one side of sill E and adjacent to knife U'.

W designates semicircular guides secured upon the upper side of platform B'', into which pins W', Fig. 7, upon sweeps T' run to guide the same in their rotary movement.

10 Sleeve S upon shaft Q'' is formed with a flange S'', against which bears a rod S''' to lift the ratchet-faced end of the sleeve from engagement with the ratchet-face Q''' of sleeve Q''' when a projection Q'''' upon flange S'' shall ride upon the same.

15 I will now describe the means employed to cause the sleeve S (which is loosely journaled upon shaft Q'') to have an intermittent rotary movement to cause the sweeps to engage in front of the cut corn to urge the same to the rear of the platform.

20 Upon the under side of collar S'' is formed the inclined projection Q'''', adapted to bear against the rod S''' and raise the sleeve when said rod is held from vertical movement. Rod S''' is held from downward movement by means of a lever X, connected with a lever X', fulcrumed upon a pin X'' upon the table, the end of the lever X being caused to move beneath the lower end of rod S''' by means of a spring X''', (shown in dotted lines, Fig. 2.)

25 the lever X being withdrawn from engagement with said rod by means of the movement of the free end of the lever X' as the passing corn contacts therewith in its movement between the edge of the table and the guides. Normally the lever X is beneath rod S''' and holds the same from being urged downward when the sleeve revolves until the

30 incline Q'''' rides upon the end of the rod and lifts the sleeve from engagement with the sleeve Q''', thereby stopping the revolution of sleeve S and the arms thereon. Sleeve S remains stationary until the end of lever X' is moved to withdraw the end of lever X from

35 beneath the rod, when the rod moves downward, permitting sleeve S to engage with sleeve Q''' and causing the arms to revolve to cause the sweeps to force the cut corn to the rear of the platform. When the pressure is removed from lever X', spring X''' causes the end of lever X to move beneath rod S''', said rod being moved vertically upward by means of a spring Y thereon, and the operation just described is repeated, thereby causing the sweeps to always move at the proper time to urge the cut corn to the rear of the machine. The arms and sweeps rest normally over the platform B'', the forward

40 sweeps being out of the stalk-passage.

To vary the inclination of the circular knife U'', the lower end of the shaft upon which the knife is keyed is journaled in a movable box Z, formed with a flange Z', which moves in a groove Z'' of a metal bar Z'', the lower portion of the box being connected with a bolt Z''', movable in a curved opening Z'''', formed in a

metal bar Z''''', secured to the framing, and by which the box may be moved laterally to vary the inclination of the shaft to cause the knife 70 to cut the corn upon an incline, thereby requiring less power than when the knife severs the corn horizontally. The said metal bar Z''' may be secured to the machine-frame in a manner similar to that in which the bar 75 Z''''' is secured.

80 a designates a standard secured in an opening in the rear portion of the base-frame and urged upward by a coiled spring b, the standard being designed to be pressed down so that the lower end rests upon the ground and held from vertical movement by means of a spring-dog c engaging with a notch or notches d, the movement of the spring-dog being effected by means of a foot-lever e, formed with 85 a projection f to engage with the enlarged head thereof.

g designates a rearwardly-extending rest against which the cut corn is moved from either side of the machine, (it being understood that the harvester is designed to harvest two rows of corn at the same time, and hence whatever description has been given of one side pertains to the opposite side, the parts being duplicates.) Divider g extends 95 rearwardly in the path of the cut corn as it is being assembled to form a bundle and tends to straighten the stalks in proper condition to be bound. When, upon a sufficient quantity of stalks being assembled, the operator pulls upon a lever h, thereby moving a lever i, fulcrumed centrally upon the platform, the opposite end of the lever i, being connected with the divider, as shown in Fig. 2, retracts the same, permitting the bundle to 105 be removed.

To move the wedge O' vertically upon standard N', a lever j is fulcrumed upon an arm k, integral with a band l, secured to the shaft. The machine is drawn forward by means of 110 animal-power attached to thills connected with the front of the machine.

In operation, the harvester being first adjusted to cause the guides and sweeps to contact with the corn at the center of weight of 115 the corn to establish an equilibrium and cause the stalks to move evenly to straighten into a compact mass, the machine is moved forward, with each sill E moving upon the outside of a row of corn. The sills B' being upon 120 the inside, the corn is caused to pass between the table and the yielding guides H and I, and also a spring-bar I'', pivoted upon the table, whereby the corn is compacted before reaching the knives, and, contacting with lever X', causes lever X to be withdrawn from supporting-rod S''', thereby permitting the sleeve S to engage with the ratchet end of sleeve Q''', causing the arms S' and sweeps T and T' to revolve, whereby the sweeps 125 strike in front of the corn and pass the same to the knives, where it is severed and urged rearward upon the lower platform upon the base-frame until it is assembled in the open-

130

ing in rear of the machine, the stalks of each side being pressed against the corresponding side of the rest *g*, when sweeps *T* and *T'*, upon being urged against the cut corn in the 5 rear of the machine, yield to the pressure by reason of spring *T'''*, and turn to allow arms *S'* to revolve past the same, when the sweeps assume their normal position. As soon as the lever *X'* is released by the passing corn 10 it flies back to its normal position, causing lever *X* to pass beneath rod *S'''*, and as sleeve *S* continues its revolution incline *Q''''* rides upon the end of the rod and raises the sleeve from engagement with sleeve *Q''*, thereby 15 stopping the revolution of the sleeve and arms *T* and *T'*. As soon as sufficient corn has been gathered in rear of the machine to form a bundle the operator pulls upon lever *h*, causing the rest *g* to be withdrawn, and then 20 presses downward upon lever *j*, causing wedge *O'* to enter slot *O''* in one of the arms *O*, when upon further pressure the wedge causes both arms to embrace the corn and press the same into a compact mass, when the operator ties 25 the bundle and, pressing his foot upon lever *e*, retracts spring-bolt *c*, allowing standard *a* to be moved by the operator's foot downwardly until it contacts with the ground, when the spring-dog is allowed to engage 30 with one of the recesses *d*, formed in the standard, thereby supporting the rear end of the frame against the weight to be put thereon in discharging the bound bundle, which is accomplished by means of the operator pushing 35 down upon lever *j* until the projections *P* engage with the arms *O* and raise the same, together with the bound bundle of corn, when upon pressing upon the lever *j* laterally the arms are caused to swing to one side and 40 deliver the bundle upon the ground in an upright position, when the operation is repeated.

It will be seen that by reason of the adjustability of the parts the harvester can be 45 adapted to corn of large or small growth, and that by reason of the adjustability of the bearing in which the knife-shaft runs any desired inclination of cut can be had—a feature of great value when the stalks are large—50 and by reason of the guides being yieldingly secured the corn is compacted before being carried to the knife, and that by reason of the intermittent revolution of the sweep and the trip mechanism which causes them 55 to revolve the sweeps are timed in their revolution to move in front of the corn just before the same is severed by the knives.

What we claim is—

1. In a corn-harvester, the combination, 60 with a rigid platform, of a vertically-adjustable platform arranged above the same and guides held in close relation with the sides and rear portions of the adjustable platform by means of yielding connections with the 65 frame to form stalk-passages for the corn around the platform, as and for the purpose described.

2. In a corn-harvester, the combination, with the main frame, of the diverging sills *E*, the upper platform vertically adjustable upon the main frame, the vertically-adjustable guide attached to the sills *E*, the inclined guides *F''*, connecting the vertically-adjustable guide and the sills *E*, and the inclined guides *D''*, connecting the vertically-adjustable platform and the main frame, and the cutting mechanism, arranged substantially as shown and described. 70 75

3. In a corn-harvester, a base-frame, a vertical post secured centrally thereof, a frame, and a platform secured thereon around which the stalks pass and provided with a tubular section adapted to fit telescopically upon the post, in combination with a lever for raising the platform and a catch for holding the 80 same in position, as and for the purpose set forth. 85

4. In a corn-harvester, a vertical shaft geared with the main shaft, a ratchet-sleeve secured thereon, a ratchet-sleeve movable 90 thereon and adapted to engage with the fixed ratchet-sleeve, a flange upon the movable sleeve formed with an incline, and a post normally bearing against the sleeve and held from downward movement by a lever beneath the same, in combination with a lever fulcrumed upon the frame, one end thereof being in the path of travel of the stalks, the opposite end being connected with the lever beneath the post, as and for the purpose set forth. 95

5. In a corn-harvester, the combination, with the upper and lower platform, constructed as described, and the guides arranged around the same to form stalk-passages, of a 105 vertical post, compression-arms movably journaled thereon, and a vertically-movable wedge adapted to engage curved slots in the arms to close the same, as and for the purpose set forth. 110

6. In a corn-harvester, a vertical post and arms mounted thereon, in combination with an upwardly-moving wedge arranged upon the post below the arms, adapted to engage slots in the arms to close the same, and formed with 115 projections to raise the arms upon the post, as and for the purpose set forth.

7. In a corn-harvester formed with two cutting sides, an upper and lower platform, and guides around the sides and rear of the same 120 to form stalk-passages, a central rest adapted to support the stalks from either side, and a lever mechanism for retracting the said rest, as and for the purpose set forth.

In testimony that we claim the foregoing as 125 our own we hereby affix our signatures in presence of two witnesses.

JAMES BLAIR GIBBS.
HENRY BOOZER.
